UNITED STATES PATENT OFFICE

2,575,144

THREAD COUNTING DEVICE

Edwin Swindells, Macclesfield, England, assignor
of one-half to Brocklehurst-Whiston Amal-
gamated Limited, Macclesfield, England, a
British company

Application May 23, 1949, Serial No. 94,890

5 Claims. (Cl. 235—91)

1

This invention relates to thread counting devices and particularly to devices for counting the warp ends for entry into heddles associated with a cross reed on an entering stand of a loom.

It will be appreciated that the selection of the appropriate number of different coloured warp threads for a required pattern is normally a lengthy and tedious business and an object of the present invention is to provide a device which will facilitate this work.

According to this invention a thread counting device comprises a thread supporting member across which the threads to be counted may extend in spaced relationship, means holding said threads against said supporting member but adapted to permit them to slide along and over one end of that member, a yielding element disposed at one end of said supporting member and adapted to be engaged successively by said threads as they slide over the end of the member whereby successive movements are imparted to said yielding element and a counter driven by said element. Preferably the supporting member is arranged transversely to the vertical and a downward force is imparted to the ends of the threads so as to maintain them in engagement with a face of the supporting member.

The end of the supporting member is slotted and the yielding element projects into said slot with a part thereof in the path of the sliding movement of said threads.

The aforesaid yielding element may comprise a toothed wheel so rotatably mounted that its teeth may pass into and out of said slot whereby the teeth are successively engaged by successive threads.

In an alternative arrangement an oscillatory mounted yielding toothed element is arranged to project into the slot so as to be successively engaged by said threads and a ratchet drive is arranged between the oscillatable toothed element and the counter.

In either of the arrangements referred to above another member may be arranged to extend along and in spaced relationship to said supporting member and the aforesaid yielding element is carried by said other member. For example, the member may be arranged to extend along and over the face of the supporting member.

The thread counting device may be mounted on an entering stand of a loom. The mounting may be such as to permit the thread supporting member to be adjustable about an upright axis and also along that axis.

The following is a description of two alterna-

tive forms of thread counting device according to the invention reference being made to the accompanying drawings in which:

Figure 1 is a diagrammatic perspective view of the thread counting device mounted on an entry stand for a loom,

Figure 2 is a side elevation of the thread supporting member and counter operating mechanism,

Figure 3 is a plan view of the arrangement shown in Figure 2,

Figure 4 is an end elevation of the arrangement shown in Figure 2 looking from the left.

Figure 5 shows an alternative form of drive for the counter.

Figure 6 is an end elevation of the arrangement shown in Figure 5 with a part of the mechanism in section.

As will be seen from Figure 1 the entering stand 10 is arranged to support in known manner the cross reed 11. The entering stand carries at its upper end a cross member 12 to which is attached a bracket arm 13 having a socket 14 at its extremity. Vertically adjustable in the socket is a rod 15 which may be secured in the adjusted position by a clamping screw 16. Mounted at the upper end of the rod 15 is a head 17 which head is secured in position by a clamping screw 18. A thread supporting bar 19 is fixed to a laterally extending boss 20 so as to extend at right angles to the rod 15. Pivotally mounted to the top of the head is a member 21 having a boss 22 in which is fixed a bar 23. A pivot pin is arranged to extend through the member 21 and the head and is provided at one end with an enlarged head 24 and at the other end with a threaded portion 25 which is engaged by a clamping nut 26. The bosses 20 and 22 are formed with projections 27 and 28 respectively, the latter of which is provided with a threaded hole engaged by a set-screw 29, the lower extremity of which abuts against the projection 27 whereby the bar 23 is held in required spaced relationship with the bar 19. The end of the bar 19 is slotted at 30 on its upper side. The end of the bar 23 carries a counter 31 which is driven by a toothed wheel 32 the teeth of which project into the slot 30. After the device has been assembled on the entering stand 10 in the manner shown in Figure 1, it is swung into a convenient position for handling the yarn ends from the warp beam or creel and for entering them into their proper position in the cross reed 11. The bar 23 is pivoted upwardly and the warp threads of one colour, say for one stripe,

2

are laid over the bar 19. The ends of the threads are tied together and have secured to them a small weight 33. The weight is sufficient to hold the threads in spaced relationship along the bar 19. The bar 23 is then lowered until the end of the set-screw 29 rests on the projection 27 when the teeth of the wheel 32 extend freely into the slot 30. It will be seen from Figure 2 that the counter is provided with a boss 34 secured to the end of the arm 23 by a 10 pin 35 and a plate 36 is provided on the underpin 35 and a plate 36 is provided on the under-side of the boss and to one side of the toothed wheel, which plate is arranged to guide the threads as they are slid along the bar into position for engaging the teeth on the wheel 32. 15 The counter is provided with a setting knob 37 for zeroizing it. The warp threads are then drawn off the end of the bar 19 one at a time and placed in the appropriate positions in the cross reed 11 on the stand 10. As each thread is drawn off the bar it slides under the plate 36 into engagement with one of the teeth of the wheel causing a partial rotation of the wheel which is so geared to the counting mechanism as to register one unit.

In the arrangement shown in Figures 5 and 6 the shaft 38 of the counter 31 has secured to it a ratchet wheel 39 by means of a pin 40. The ratchet wheel is provided with a boss 41 on which is rotatably mounted a casing 42 having a downwardly extending finger 43 which passes into a slot 44 at the end of the arm 19. Pivotedly mounted at 45 within the casing is a pawl 46 which may engage the teeth of the ratchet wheel. The arrangement is such that as the warp threads are slid along the bar 19 between it and the plate 16, they engage the finger 43 rotating the casing 42 clockwise, whereupon the pawl 46 engages a tooth of the ratchet wheel. Eventually the thread passes clear of the finger 43 and the bar 19, whereupon the weight of the finger rotates the casing anti-clockwise and the pawl will be carried over the succeeding tooth. In order that the return movement of the finger 43 may be limited the finger is arranged to extend through a loop 47 fixed to the bracket 48 which supports the counter 31.

I claim:

1. A thread counting device comprising a thread supporting member across which the threads to be counted may extend in spaced relationship, loading means securing together the ends of the threads and holding said threads against said supporting member and permitting them to be slid along and over one end thereof, which end is provided with a slot, a yielding element projecting into said slot having a part thereof in the path of the sliding movement of said thread so as to be successively engaged by said thread and have successive movements imparted thereto, and a counter driven by said yielding element.

2. A thread counting device comprising a thread supporting member across which the threads to be counted may extend in spaced relationship, loading means securing together the ends of the threads and holding said threads against said supporting member and permitting them to be slid along and over one end thereof, which end is provided with a slot, a toothed wheel so rotatably mounted that its teeth may pass into and out of said slot and when in the slot have a

part thereof in the path of sliding movement of the threads so that said wheel has imparted thereto successive partial rotations as the threads are passed over the end of the supporting member, and a counter driven by said wheel.

3. A thread counting device comprising a thread supporting member across which the threads to be counted may extend in spaced relationship, loading means securing together the ends of the threads and holding said threads against said supporting member and permitting them to be slid along and over one end thereof, which end is provided with a slot, an oscillatably mounted yielding toothed element projecting into said slot so as to be successively engaged by said threads during their sliding movement over the end of said supporting member, whereby the element is moved in one direction, loading means for moving it in the opposite direction, a counter, and a ratchet drive between the counter and said oscillating toothed element.

4. A thread counting device comprising an upright, a thread supporting member fixed at one end to said upright so as to extend transversely thereto and across which supporting member said threads extend in spaced relationship, loading means securing together the ends of the threads and holding said threads against said supporting member and permitting them to be slid along and over one end thereof, a second member pivotally mounted above said supporting member with its pivot axis adjacent said upright means holding said threads against said supporting member but adapted to permit them to be slid along and over the end thereof, which end is provided with a slot, a yielding element carried by said member so as to extend into said slot and so as to lie in the path of sliding movement of said threads whereby successive movements are imparted to said yielding element, a counter driven by said yielding element, and means for adjusting the extent of pivotal movement of said member towards the supporting surface.

5. An entering stand for a loom having a socket attached thereto, an upright rod rotatably and axially adjustable in said socket, a head at the upper end of said rod, two bars mounted one above the other on said head, the lower of which bars is fixed and constitutes a supporting member for the threads which extend across it and are slidable along it over its end and the upper of which bars is pivoted to swing in an up-and-down direction, a slot at the end of the fixed bar, a yielding element carried by the upper bar and projecting into said slot and having a part thereof in the path of sliding movement of said threads as they are slid over the end of said member so as to impart successive movement to said yielding element, and a counter driven by said element.

EDWIN SWINDELLS.
